UNITED STATES PATENT OFFICE.

MARTIN W. JOYCE, OF NEW YORK, N. Y., ASSIGNOR TO JOHN H. WIEMERS, INC., OF NEW YORK, N. Y., A CORPORATION OF NEW YORK.

CLOTH-REEL.

1,272,672.

Specification of Letters Patent. Patented July 16, 1918.

Application filed April 17, 1918. Serial No. 229,047.

To all whom it may concern:

Be it known that I, MARTIN W. JOYCE, a citizen of the United States, residing at New York, in the county of New York and State 5 of New York, have invented a certain new and useful Improvement in Cloth-Reels, of which the following is a full, clear, and exact description.

The object of this invention is to provide 10 in an economical way, a simple and durable reel on which to wind cloth, veiling and other textile materials.

Such reels have been made wholly of wood, and also of a wooden frame covered 15 with paper, pasteboard and other material, and they have been made wholly or partly of other substitutes for wood. The present invention relates to that type of reel where a wooden frame is used, covered with paste- 20 board, boxboard or equivalent relatively stiff, lightweight and durable material.

So far as I know the prior art, the present invention differs from it in the use of a single longitudinal strip of wood or other 25 penetrable material, arranged centrally in connection with two transverse end strips of similar material, the central strip and the end strips being unconnected preferably excepting through the application of the 30 cover, and the cover being creased so as to be capable of being folded over the end strips and longitudinal strip, and all united by staples or other fastenings, such as tacks, 35 nails, wires or the like.

In the accompanying drawings illustrating 40 the invention, in the several figures of which like parts are similarly designated, Figure 1 is a perspective view of the assembled parts without the central and end 45 finishing strips. Fig. 2 is a plan view of the finished reel. Fig. 3 is a transverse section, on a larger scale, taken in the plane of line III—III of Fig. 2. Fig. 4 is a plan view of a portion of the cover, designed to

show the creasing. 50 The frame comprises a longitudinal strip 1 of wood, or equivalent material penetrable by driven fastenings, such as staples, nails, tacks, wires and the like, and two end strips 2 of similar material arranged transversely at the ends of the longitudinal strip. It is not necessary to join or connect the end strips 2 with the longitudinal strip 1.

The frame thus made is covered with a 55 cover 3 made of pasteboard, boxboard or

equivalent flexible material which may be and preferably is creased longitudinally as at 4, Figs. 3 and 4, so as to be capable of being bent symmetrically about the ends of the end strips 2, with the meeting ends 5 60 of the creases as described, it also has sufficient stiffness of body to form the definite and permanent longitudinal edges of the reel, without danger of collapsing under the load placed upon the reel, and without the necessity of using auxiliary longitudinal 65 edge-supports for the cover between the end strips such as have been employed in prior constructions of built-up or composite reels. The operation of creasing not only defines 70 the folds but also fixes the lines of the longitudinal edges of the finished reel. Further, the stiffness of the cover material is such as to render the cover self-sustaining 75 when applied to the frame.

When the longitudinal mid-strip, the end 80 strips 2 and the cover 3 are assembled or arranged as shown in Fig. 1, the parts are united by means of staples 6 or other suitable, preferably driven fastenings, which connect the meeting ends of the cover and 85 bind them securely to the longitudinal strip, the fastenings preferably extending entirely through the structure and their ends turned into the cover material at the back, as shown in Fig. 3. Fastenings 7 are driven similarly 90 through the cover into the end strips to unite these parts. In order to conceal the fastenings and afford a symmetrical finish to the reel, I may cover them and the meeting 95 ends 5 of the cover by means of a strip 8 with a similar strip 9 on the back, and the ends of the reel may be similarly covered 100 with strips 10, the strips 8, 9 and 10 being of paper, textile material, or other suitable material or fabric.

As already indicated, the frame composed of the single longitudinal mid-strip 1 and the end strips 2 may be arranged without previously connecting or joining them; the cover 3 may have the longitudinal creases 4 105 at opposite equidistant places, so as to be foldable, without breaking and in a symmetrical manner, over the ends of the end strips, to form the longitudinal edges and body portions of the reel, and then these 110

parts may be permanently assembled by means of a stapling or equivalent fastener applying machine which applies the staples 6 and 7 or other driven fastenings, as previously stated.

By the construction described, very durable, strong, light and compact reels may be produced at a relatively small cost. The cover may be creased longitudinally in an 10 ordinary creasing machine, and then the cover and the wooden frame members united by a stapling, nailing or other fastener-driving machine, and without the use of glue or paste.

15 The splitting of the cover indicated at the ends of Fig. 3, may or may not occur in bending the cover over the frame, and depends more or less upon the laminal character of the material of the cover and the 20 creasing.

So far as I am aware, it is new to construct a reel of a skeleton frame covered with a cover of fibrous material creased or 25 grooved longitudinally along the folds, and the cover secured to the frame by driven fastenings. In prior constructions using fibrous covers folded over a frame, such covers have been simply bent over the frame and held in place thereon by glue or similar adhesive.

30 Variations in the details of construction and arrangement of parts are contemplated as within the principle of the invention as hereinafter claimed.

35 What I claim is:

1. A cloth reel, having a wooden frame, and an inclosing self-sustaining cover, said

Copies of this patent may be obtained for five cents each, by addressing the "Commissioner of Patents, Washington, D. C."

frame comprising only a longitudinal mid-strip and transversely arranged end strips, 40 said cover folded over the frame and secured to the mid-strip and end strips and its longitudinal folds forming the longitudinal edges of the reel.

2. A cloth reel, having a wooden frame, and a longitudinally folded self-sustaining 45 inclosing cover, said frame comprising a single longitudinal strip arranged centrally of the reel, and end strips arranged transversely to the longitudinal strip, the cover being folded over the longitudinal and end 50 strips with its meeting ends abutting over the longitudinal strip, and driven fastenings securing the cover to the longitudinal strip and the end strips, said cover alone forming the longitudinal edges of the reel. 55

3. A cloth reel, having a frame, and an inclosing self-sustaining cover, the frame comprising a single longitudinal mid-strip and transversely arranged end strips, said cover folded over the strips and its meeting ends 60 abutting over the mid-strip, driven fastenings applied to the cover and mid-strip and end strips and penetrating the several thicknesses and thereby permanently uniting the cover and frame, and finish covers applied 65 to the frame-inclosing cover to conceal the fastenings.

In testimony whereof I have hereunto set my hand this fifteenth day of April, A. D. 1918.

MARTIN W. JOYCE.
